2 SHEETS—SHEET 2.

UNITED STATES PATENT OFFICE.

CHARLES W. BALLOU, OF SELLERSBURG, INDIANA.

CURTAIN-STRETCHER.

No. 908,640.

Specification of Letters Patent.

Patented Jan. 5, 1909.

Application filed February 15, 1908. Serial No. 416,155.

To all whom it may concern:

Be it known that I, CHARLES W. BALLOU, a citizen of the United States, residing at Sellersburg, in the county of Clark and State 5 of Indiana, have invented certain new and useful Improvements in Curtain-Stretchers, of which the following is a specification, reference being had to the accompanying drawings.

10 My invention relates to improvements in curtain stretchers, and consists of the novel features of construction and the combination and arrangement of parts hereinafter fully described and claimed.

15 The object of the invention is to provide a simple and practical device of this character in the form of an adjustable upright frame over which the curtain to be stretched is thrown and secured upon its opposite 20 sides.

The above and other objects of the invention are attained in its preferred embodiment illustrated in the accompanying drawings, in which—

25 Figure 1 is a front elevation of my improved curtain stretcher, showing the parts adjusted for a wide curtain; Fig. 2 is a vertical longitudinal section through the same, but showing the parts adjusted for stretching 30 a small size curtain; Fig. 3 is a vertical transverse section taken on the plane indicated by the line 3—3 in Fig. 1; Fig. 4 is a horizontal section taken on the plane indicated by the line 4—4 in Fig. 1; and Fig. 35 5 is a detail view of the locking device for the hinge joint of one of the sectional members or bars.

My improved curtain stretcher comprises 40 two similar upright end members 1, 2 which are adjustably connected by one or more longitudinal members or bars 3, 4, 5. Each of the upright members 1 has an enlarged base portion 6 which provides a substantial support for the frame so that it cannot be 45 overturned, and upright side portions or bars 7 which rise from the base 6 and are spaced apart, adjacent their upper ends, by cross portions 8 so as to provide in the upright end members vertical openings or slots 50 9 to receive the bars or members 4, 5. The extreme upper ends of the side bars 7 extend above the connecting portion or block 8 to form a recess or seat for the upper bar or member 3.

55 The upper bar 3 is preferably of greater length than the widest curtain that is to be

stretched upon the device and one of its ends is hinged to one of the upright end members, preferably the member 1, by a strap hinge 10 so that said bar 3 may be folded downwardly against the member 1 when the device is to be stored away or transported. The free end of the bar or member 3 is adapted to slide in the recess or seat in the top of the upright end member 2 and to be 60 secured in an adjusted position therein by a removable pin 11 which is passed through transversely alining apertures in the upper ends of the bars 7 of said member and through any one of a longitudinal series of 70 transverse apertures 12 formed in the bar or member 3. The pin 11 is straight and has at one end a finger piece or head whereby it may be readily inserted in and removed 75 from the apertures in said parts 3, 7.

The lowermost longitudinal connecting bar or member 5, which I will term the base bar, has one of its ends connected by a strap hinge 12' to one of the upright end members, preferably the member 2, and its upper 80 end is adapted to project through the slot or opening 9 in the other member 1. The base bar or member 5 is adapted to be folded upwardly against the member 2 when the stretcher is not in use, and it is adapted to 85 be secured in its operative position to space the base portions of the members 1, 2 apart and steady the frame, by pivoting upon said members 1, 2, hooks 13, 14 which are adapted 90 to engage staples or other suitable keeper eyes 15, 16 upon said bar 5, as clearly shown in Fig. 1. A longitudinal series of the staples or eyes 15 is provided for the pivoted hook or catch 13 to allow for the adjustment 95 of the member 1.

The intermediate longitudinal bar 4, which I will term the lower curtain stretching bar or member, is vertically adjustable in the slots 9 in the end members 1, 2, preferably by providing in the side bars 7 of 100 said members vertical series of transversely alined apertures 16 to receive removable pins 18, 19 which are similar to the pins 11. The pin 18 pivots and secures one end of the bar 4 to the end member 1 and the pin 19 secures the other end of said bar in the other end member 2. To allow for the adjustment of the two end members toward and from each other, a longitudinal series of apertures 20 105 is formed in the bar 4 for the reception of the pin 19.

In order to prevent the ends of the bars or

members 4, 5 from projecting beyond the end members 1, 2 when the frame is adjusted for stretching a small size curtain, I make each of said bars of two sections 21, 22 and 5 connect them by strap hinges 23, as more clearly shown in Fig. 5. By thus hinging the outer sections 22 to the inner sections 21, the former may be swung upwardly alongside of the end members or into the openings therein, as shown in Fig. 2 when the frame is adjusted for a small curtain. For the purpose of securing the sections 21, 22 in longitudinal alinement when the stretcher is adjusted for a larger curtain, I provide 10 the locking device which is shown in Fig. 5 and which consists of a plate 24 pivoted at 25 upon the section 21 and having at its free end a notch 26 to receive a clamping bolt 27 that passes through the other section 20 22 and has a winged nut 28 upon its threaded end.

The curtain to be stretched is thrown over the upper stretching bar 3 of the frame, the upper edges of which bar are rounded as 25 shown at 29 in Fig. 3 so that the curtain will not be creased at such points after it has dried and is removed from the device. The side edges of the curtain are fastened to the side bars 7 of the end members by engaging 30 said edges with suitable fastening devices 30 which are here shown in the form of small pins or hooks, and which may be of any other suitable form and construction. The inner edges of the side bars 7 have their 35 outer faces, from which the pins or fasteners 30 project, beveled and grooved, as shown at 31 in Fig. 4, to reduce said bars 7 in thickness so that the two hanging end portions of the curtain may lie in vertical planes close 40 to the vertical planes of the opposite side faces of the upper stretching bar 3. The upper ends and the inner corners of the bars 7 are also reduced and rounded as shown for a similar purpose. The top and 45 bottom edges of the curtain are fastened to the opposite side faces of the lower stretching bar 4 by engaging them with pins 32 which project from said faces of the bar 4 and are similar to the pins or fasteners 30. 50 By making the pins or fasteners 30, 32 of suitable length and shape, a number of curtains of the same size may be simultaneously stretched upon the device.

To facilitate the adjustment of the 55 stretcher for the reception of a curtain of known width and length and for the further purpose of enabling the curtain to be stretched evenly or squarely upon the device, I preferably provide the outer side 60 faces of the bars 3, 4 and 7 with graduation marks 33, as clearly shown in Fig. 1.

Having thus described my invention what I claim is:

1. A curtain stretcher comprising upright 65 end members, upper and lower longitudinal

bars each hinged at one end to one of the end members to fold against the same, adjustable connections between the other ends of said longitudinal bars and the opposite end members, an intermediate longitudinal bar 70 vertically and longitudinally adjustable upon the end members, said intermediate and lower longitudinal bars each having a main section, and a foldable section, hinges connecting said sections of each of said sectional bars, means for holding the sections of each of said sectional bars in longitudinal alinement and curtain attaching means upon the outer faces of the intermediate longitudinal bar and said end members. 75

2. A curtain stretcher comprising upright end members each having enlarged base portions, spaced parallel side bars projecting from the base portion, spacing blocks between said side bars adjacent to their upper 80 ends, an upper longitudinal bar adapted to rest upon said spacing blocks and between the projecting upper ends of the side bars, a strap hinge connecting said upper longitudinal bar to the spacing block on one of the 85 end members to permit said upper bar to fold against said end member, said upper longitudinal bar being formed adjacent to its other end with a longitudinal series of apertures adapted to align with apertures 90 formed in the projecting upper ends of the side bars of the other end member, a removable pin passed through the registering apertures in said side bars and the upper longitudinal bar, a lower longitudinal bar arranged 95 between the spaced side bars of the end members and resting upon the base portions of the latter, a hinge connecting said lower bar to the base portion of one of the end members, a plurality of eyes arranged 100 upon the lower bar, hooks carried by the base portions of the end members and engaged with said eyes, an intermediate longitudinal bar arranged between the spaced side bars of the end members and formed 105 with a plurality of apertures to register with alining apertures formed in the spaced side bars of the end members, removable pins arranged in said registering and alining apertures in the intermediate and side 110 bars to adjustably secure the former between the latter, said intermediate and lower longitudinal bars each having a main section and a foldable section, hinges uniting the two sections of each of said sectional 115 bars, fastening means between the sections of said sectional bars to hold their sections in alinement and curtain engaging pins projecting from the opposite side faces of the intermediate longitudinal bars and the side 120 bars of the end members.

3. A curtain stretcher comprising upright end members having enlarged base portions, upper and lower longitudinal bars adjustably connecting said end members, an inter- 125

mediate bar vertically and longitudinally adjustable upon the end members, said lower longitudinal bars each having a main section and a foldable section, the latter being hinged to swing to a vertical position to permit the stretcher to occupy but little space when adjusted to receive a small sized curtain, and curtain attaching means upon the

outer faces of the intermediate longitudinal bar and said end members.

In testimony whereof I hereunto affix my signature in the presence of two witnesses.

CHARLES W. BALLOU.
